UNITED STATES PATENT OFFICE.

SYLVIA S. JUDSON, OF CHICAGO, ILLINOIS.

DESIGN FOR A HANDLE FOR FAUCETS OR THE LIKE.

Application filed February 17, 1928. Serial No. 25,468. Term of patent 14 years.

To all whom it may concern:

Be it known that I, SYLVIA S. JUDSON, a citizen of the United States, residing at Chicago, county of Cook, State of Illinois, have invented a new, original, and ornamental Design for a Handle for Faucets or the Like, of which the following is a specification, reference being had to the accompanying drawing forming a part hereof, wherein—

Figure 1 is a side elevation of a faucet having a handle embodying my new design; and

Fig. 2 is a front elevation of the faucet and handle of Fig. 1.

I claim:

The ornamental design for a handle for faucets, or the like, as shown.

SYLVIA S. JUDSON.
